UNITED STATES PATENT OFFICE

WILLIAM E. TRENHOLM, OF EVELETH, MINNESOTA

BATHING-BEACH FLOAT

Application filed March 19, 1928. Serial No. 262,720.

This invention relates to floats and has special reference to a bathing beach float particularly adapted for use in water sports.

The principal object is to produce a device 5 of this character having novel and attractive features for the practice of water sports.

Other objects and advantages of the invention will appear in the further description thereof.

10 Referring now to the accompanying drawings, forming part of this application and wherein like reference characters indicate like parts:

Figure 1 is a top plan view partly in section 15 of one of my improved floats; and

Figure 2 is a section taken on the line 2—2 of Figure 1, and somewhat enlarged.

1 represents a platform or deck mounted upon two spaced floats 2 of any desired construction; the two here shown being air tight 20 rectangularly shaped tanks, one adjacent either end of the deck 1.

Intermediate of these tanks and dependingly supported in any desired manner as by 25 the brackets 3 is mounted the shaft 4, extending transverse the deck 1 and to some considerable distance therebeyond.

Upon either projecting end of this shaft is mounted a hollow, water tight elongated cylinder 5, preferably made of metal and covered with a heavy ribbed rubber matting 6; these cylinders being loosely and rotatably mounted upon the shaft. The outermost ends of the cylinders I propose to have convex or 35 dish-like so as to permit of the holding nut 7 being inboard of a plane with the end of the cylinders to avoid danger of one playing with the device fouling themselves thereupon.

To the shaft 4 and centrally beneath the 40 deck I have shown a clamp 8 fixed thereto and to which the anchor chain 9 is attached, or as is obvious this attachment of the anchor chain may be accomplished in any other desired manner so that the float may be anchored any 45 place desired in the water.

Mounted upon either end of the deck I have 50 illustrated an inclined ladder 10 which may terminate upwardly above the deck in the arched rail like structure 11, and the lower portion of the ladder being provided with

suitable spaced rungs 12 provides convenient means for mounting the float from the water.

As a means for holding the shaft 4 in position I have shown a set collar 13 mounted thereupon just inboard of the brackets 3. 55

From the foregoing it is evident that I have devised a very practical and attractive float having extending therefrom the cylindrical rotatable floats independently of each other upon which the sport of log rolling may be 60 practiced in a most interesting and fascinating manner, and that various modifications of the device as here shown may be resorted to without departing from the spirit of the invention. 65

Having thus described my invention, what I claim and desire to secure by Letters Patent, is:

1. A float of the class described comprising a buoyant body portion, and a rotatable 70 buoyant member extending laterally from the body portion for the purpose described.

2. A float of the class described comprising a buoyant body portion, having extending from either side thereof an independent, 75 buoyant, rotatable cylinder for the purpose described.

3. A float of the class described comprising a body portion, and spaced independently rotatable, buoyant cylinders attached to said 80 body portion, and means for anchoring the float.

4. A float of the class described comprising a body portion, and laterally extending rotatable cylinders attached to said body portion for the purpose specified. 85

In testimony whereof I affix my signature.

WILLIAM E. TRENHOLM.
